ABSTRACT

A match package formed from a cut and scored blank and adapted to hold matches in its tray portion and to be secured to a cigarette pack, said match package comprising

a tray portion, including a back and opposed side and end walls, and
a striking strip,
each side wall including an attaching flap at its opposed ends, a medial flap midway between the ends thereof,
each end wall including a flap cover foldably connected to an outer edge, being the same width as said back wall, and substantially half the length thereof,
said attaching flaps being secured to end walls to form said tray portion, and
an attaching element securing the striking strip, matches, and both medial flaps to said back wall with the said flap covers being adapted to be tucked under said striking strip to close said match package.

2 Claims, 5 Drawing Figures

FIG. 1

FIG. 3

FIG. 2

FIG. 4

FIG. 5

CIGARETTE MATCHES

This invention relates to a combined cigarette package and match package, with special reference to a new and improved match package attached and packaged with cigarette packages.

The first important object of the invention is to provide a match package which might be constructed from a thinner, less expensive material than the present match books, due to its box-like construction, whereas the sides of the match package provide the necessary stiffness, but protect the matches and cigarettes from breaking or crushing.

The second important object of the invention is to provide a handy, inexpensive and convenient lighting device, with emphasis on convenience. The new and improved match package is attached to either side of a cigarette package by the cigarette manufacturer while packaging cigarettes and provides this convenience for the smoker.

The third important object of the invention is to provide a container with based dimensions corresponding to the side dimensions of a cigarette package.

The fourth important object of the invention to provide a striking surface for the matches, and means for holding the match package matches, and striker strip together.

Other objects and advantages of the invention will be readily understood when described in connection with the accompanying drawings, in which

FIG. 1 is a perspective view of the match package attached to a partially illustrated cigarette package;

FIG. 2 is a plan view of a blank from which the match package is constructed;

FIG. 3 is a side view of a partial cross section of an assembled match package;

FIG. 4 is a plan view of the match strip; and

FIG. 5 is a plan view of the striker strip.

Referring to the drawings, in FIG. 2 is shown a blank of thin cardboard, plastic or like inexpensive material, the match package comprising a substantially rectangular tray portion, measuring in width and height substantially the same as either side of a cigarette package, proportionately smaller or larger for Regular, King or 100 mm. cigarette packages. Each side wall 11 is scored at the lines 12 of the back 10 and converging inwards from one end of its respective side toward the medial flap 22, then diverging outwardly to its opposite respective end. The ends of each sidewall 11 are slightly taller, to cover the two rows of match heads located at both top and bottom ends of the tray portion.

Attaching flaps 13 are formed at the opposed ends of both side portions 11 and are scored at lines 14, and are foldably connected to the top and bottom end walls 16.

Each end wall including a flap cover, said covers 17 are rectangular in size, extending from the outer edge of the end walls, substantially to the middle of the match package, being substantially the same width as the back 10 and fully covering the matches when tucked under the striker strip 19.

The match strips 20 shown in FIG. 4 are constructed of the usual cardboard material presently employed making book matches, measuring to size to fit in the constructed tray portion, with a slight margin around it. The length of the matches depend on the size of the cigarette package, but the width remains the same in most cases. The match strips consisting of five match heads on both ends of the strip, and a blank space 21 in the

center. Two of these match strips are then placed in the center of the tray portion, and the medial flaps 22 being substantially midway of the side portions 11 folded inwards, toward the center of the match package, over the blank space 21 of the match strip 20. The combination cover holder/match igniter strip, referred here as striker strip 19, being rectangular in shape, its length being substantially the same as the back wall 10 and two-thirds the width thereof, made of the same or thicker cardboard or like material as the body of the match package itself, coated with match igniting surface, and placed in the center of the match package over the match strips 20 and folded medial flaps 22. Attaching means, such as staple 23 holds the striker strip 19, the two match strips 20, the side portions 11 with the employment of medial flaps 22, and securing to the bottom of back 10 of the match package. The flap covers 17 folded at the creased lines 18 and being adapted to be tucked under the striker strip 19 to close said match package. Adhesive applied to either sides of the cigarette package, or the bottom part of back 10, to hold the match package in place as shown on FIG. 1. The outer surface of the match box may be printed in colors of the particular brand of cigarette package it is attached to, and may bear printing of the brand name, or other texts or insignias thereon, to conform to manufacturer's specifications.

To preserve freshness of cigarettes, most brands are wrapped in cello outer wrapper. This outer wrapper 30 may also cover the match package, and on the outer sides of the side portions 11 and the outer side of end walls 16 adhesive may be applied. The cello wrapper may be rouletted or otherwise made easily separable, in a rectangular shape around the upper perimeter of the match box, for the purpose of easy separation at the time of opening the cigarette package. The cello wrapper adhering to the sides and bottom of the match package, provides continuous protection of the cigarettes after the package is opened.

40 Minor changes in application, form, construction and material may be made without departing from the spirit of the invention, such as adapting the said invention for cigar packages, tobacco pouches or the like; therefore, it is not desired to confine the invention to the exact form described as shown, but to include any and all minor changes which may properly come within the scope claimed.

What is claimed as new is:

1. A match package formed from a cut and scored 50 paperboard blank or the like and adapted to be secured to a cigarette pack, said match package comprising a substantially rectangular tray portion, including a back and opposed side and end walls, and a substantially rectangular striking strip, each side wall including an attaching flap at its opposed ends and a medial flap on a longitudinal outer edge substantially midway between the ends thereof, each side wall outer edge converging inwardly from one end of its respective side wall toward said medial flap and then diverging outwardly to its opposite respective, and, each end wall including a flap cover foldably connected to an outer edge thereof, each flap cover being substantially the same width as said back wall and substantially half the length thereof, said striking strip includes a match igniting surface, its length being substantially the same as the width of said back wall and substantially two-thirds the

width thereof,
said attaching flaps being secured to said end walls to
form said tray portion, and
an attaching means securing the striking strip and
both medial flaps to said back wall with the said
flap covers being adapted to be tucked under said

striking strip to close said match package.
2. A match package as claimed in claim 1 wherein a
plurality of match strips are attached to the back wall
within the confines of said tray portion by said attach-
ing means.
